Primary Examiner — Catherine Ho

(74) *Attorney, Agent, or Firm* — Connie R. Masters

(57) **CLAIM**

The ornamental design for a card holder, as shown and described.

DESCRIPTION

FIG. 1 is a front perspective view of a card holder, showing my new design;

FIG. 2 is a back perspective view thereof;

FIG. 3 is a front side view thereof;

FIG. 4 is a back side view thereof;

FIG. 5 is a top view thereof;

FIG. 6 is a bottom view thereof; and,

FIG. 7 is a right side view thereof, the left side view being a mirror image thereof.

The evenly dashed broken lines show portions of the card holder that form no part of the claimed design. The dash-dot-dash broken lines show environment that form no part of the claimed design.

1 Claim, 3 Drawing Sheets
